CHARLES S. KENDALL, OF NEW YORK, N. Y.

TIDE AND WAVE MOTOR.

No. 925,581.

Specification of Letters Patent.

Patented June 22, 1909.

Application filed April 4, 1908. Serial No. 425,086.

To all whom it may concern:

Be it known that I, CHARLES S. KENDALL, a citizen of the United States, residing at the borough of Brooklyn, county of Kings, city and State of New York, have invented certain new and useful Improvements in Tide and Water Motors, of which the following is a specification.

This invention relates to an improvement 10 in devices for utilizing water for the purposes of generating continuous power, and the object is to provide an apparatus whereby by the rise and fall of the tide either of the sea, river, tributary streams, and reservoirs 15 connected therewith may be utilized to produce power for the operation of machinery of various kinds and for various purposes, the results being accomplished both in the rise and in the fall of the tide, or other rise 20 and flow of water operating upon the device which I have invented.

With this and other objects in view, the invention consists in certain constructions and combinations of parts which will be 25 hereinafter fully described and then specifically pointed out in the claims hereto appended.

In the accompanying drawings, which form part of this specification, and in which 30 like characters of reference indicate the same parts, examples of my invention are disclosed.

Figure 1 is side view of an example of my invention, in which the tank is shown in full 35 lines at its lower position, and in dotted lines at its higher position. Fig. 2 is a sectional view of part of Fig. 1, indicated by the line A, B, looking in the direction of the arrow. Fig. 3 is a top view of a device to which 40 power may be applied by my invention, and such as is indicated connected with the device shown in Fig. 1. Figs. 4, 5, 6, 7 and 8 are views of details.

In carrying out the invention, I provide 45 one or more suitable tanks, such as or similar to the one shown at 1, which is arranged to float upon the water at low tide, and is placed in position within a suitable frame. This frame may be constructed of base 50 pieces, 2, 2, uprights 3, 3, and suitable braces, 4, 4. The parts are suitably and firmly secured and braced to each other at desired points by angles, as the pieces 5, 5, and across the top of the frame, extending to 5 any required distance, and supported in any suitable manner, is a bearing part or way, 6,

The tank or vessel 1, which may be conveniently made of any suitable material, and of any desired shape, is water tight, and is provided with two or more guide rollers, 60 7, 7, which impinge and move against uprights, 8, 8, by which the up and down movements of the tank, 1, are preserved substantially straight up and down. The tank, 1, may be braced with metal straps and connecting parts, as 9, 10, 11, 12, etc., as may be desired, depending upon the size of the tank. At each corner of the tank the above metal parts, as 9, 11, are secured, and to the lower ends of these and to the lower end of the 65 part 10, arranged intermediate between them ropes or chains, 13, 13, 13, are attached, which are carried to a central point under the tank, 1, as indicated in Fig. 2. Beneath the tank at the central point mentioned, a pulley, 14, 70 75 is strongly secured to one of the base pieces, 2, and in line therewith, and near one end of the frame, another pulley, 15, is likewise secured. To the central connecting point of the ropes or chains, 13, 13, another rope or 80 chain, 16, is attached, and this is carried downward and beneath the pulleys, 14, 15, and thence upward and over a pulley, 17, on the bearing way, 6, and forward against a horizontal pulley, 18, on the same part, 6. 85 The metal pieces, 9, 10, 11, at their upper ends, are also provided with ropes or chains, 19, 19, 19, which are gathered to a central point above the tank, and to these a rope or chain, 20, is secured, the arrangement of 90 these ropes or chains at the upper part corresponding to the similar arrangement at the bottom of the tank, 1. The rope or chain, 20, is carried upward, and over a pulley, 21, arranged on the bearing way, 6. This pulley, 21, may be higher than the pulley, 17, or to one side of the pulley, 17, and the rope or chain, 20, is carried against the pulley, 22, arranged above or beside the pulley, 18, and thence forward, as will be described, and as 95 shown in the drawings.

The two figures of the tank, 1, shown in Fig. 1, represent the same tank in different positions, the lower representation indicating the position of the tank at low water, the upper representation indicating the tank at high water. The tank, 1, is furthermore provided with one or more openings, to each of which a double acting closing device is attached. This closing device consists of 100 two valve closing plates or leaves, one, 23, to close the opening at the inner face of the

22

tank, and one, 25, to close the opening at the outer face of the tank, each of which is provided with a rubber piece, 24, 24, chamfered at the edges to fit tightly into the opening of the tank, one on its outer face, the other is provided with a similar piece, to fit tightly into the opening of the tank on its inner face. The two plates forming this closing device, are arranged to move or swing upon a journal, 26, so that when one part is held against the opening in the tank the other is drawn away therefrom. To the inner plate, 23, of this closing device an arm, 27, is attached, and to this a rope or chain, 28, is attached, which chain is carried up to a hold fast, 29, and secured there in such adjustment that when the tank, 1, is at the lowest point of its movement, the interior leaf or part 23 of the closing device is drawn up by the chain, 28, and the opening in the tank is closed, the tank, 1, then being empty and light. As the tank, 1, is carried up by the rising water, the chain, 28, falls into the tank, but the opening in the same is held closed by the pressure of the water on the outer leaf, 25, of the closing device. In its continued upward movement, however, a tripping leg, 30, on the hold fast, 29, passes into the tank, and engages the inner leaf 24 of the closing device, gradually forcing out the outer leaf 25 thereof. This tripping device may be provided with friction roller or rollers, 31, as shown in Figs. 4 and 5. As soon as the opening is thus freed the water rushes into the tank, the adjustment of the parts being such that the tank is substantially filled and loaded with water before the inner leaf 23 of the closing device is forced against the opening by the part 30, and when it is forced fully against the opening on the inner side of the tank, the weight of water in the same keeps the leaf 23 firmly against the opening, thus retaining the water in the tank, and weighting the same for its work as it descends with the outgoing tide. As soon, however, as the tank reaches the desired point in its descent, the chain, 28, according to the adjustment, gradually draws up the inner leaf 23 of the closing device, permitting the water in the tank to escape, until the tank reaches a point at which it is substantially emptied, at which point, according to the adjustment of the parts, the outer leaf 25 of the closing device is forced and held against the opening in the tank, by the pressure of water from without. In other words, the adjustment of the parts is such that for a part of the movement of the tank, 1, the opening in the tank is closed by the pressure of water within the tank, and for a part of the movement the opening in the tank is closed by the pressure of the water without the tank. Thus the light and empty tank moving upward, draws up with it the rope or chain, 16, and the weighted tank moving downward draws down with it the

rope or chain, 20. The power thus generated may be employed in any manner desired. I show herein one of the ways in which it may be employed.

At a suitable point a standard or other support is provided, on which a gear wheel 33 may be mounted horizontally on a suitable journal, 34. On this same journal and operatively connected with the gear, 33, two pulleys, 35 and 36 are secured with their peripheries hollowed out suitably to take in and choke the ropes passing around them. Or in case it is desired, these pulleys, 35 and 36, may be replaced by sprocket wheels, and the ropes by suitable chains to engage therewith.

The adjustment of the ropes or chains, 16 and 20 to each other, and to the pulleys, 35 and 36, is such that when the tank, 1, is at the lowest point of its movement, and commences to rise, the rope, 20, is substantially slack, having performed its work as the tank descended. The situation of the ropes, 16 and 20, in Figs. 1 and 3, is shown at the point where the tank commences to rise. It must be noted that in the example of the invention shown in the drawing, the rope, 16, is vertically below the rope 20. The outer end of 16 is joined to 20 at the point marked 43, in Fig. 3, and the outer end of the rope 20 is joined to 16 at the point marked 44, in Fig. 3, and in that figure the rope 20 is broken away on the lower edge of Fig. 3 in order to show the rope 16 below it. As the tank commences to rise, the rope, 16, on the lower part of the tank commences to draw the pulley, 36, in the direction of the arrow, as shown in Fig. 3. At the desired point on the rope, 16, the outer end of the rope, 20, is secured, in such adjustment that, as the tank rises and the rope, 20, slackens, the slack part thereof is taken up by the movement of the rope, 16, so that the rope, 20, which passes around the pulley, 35, is held substantially taut, during the entire upward movement of the tank. The outer end of the rope, 16, correspondingly is attached to the rope, 20, in similar adjustment, that is to say, when the tank, 1, has reached its highest position, and commences to descend, the rope, 20, having had its slack taken up by the movement of the rope, 16, now commences to turn the pulley, 35, also in the direction of the arrow shown in Fig. 3, and in its movement takes up the slack of the rope, 16, so that that rope remains substantially taut, as the tank descends. To the larger gear wheel, 33, a smaller gear, 37, is connected which is attached to a shaft, 38, which shaft may be suitably supported, extended and connected to other gears to multiply the movements of the device or utilize the same in any manner desired.

For clearness, details of parts have been separately shown. Fig. 4 is a side view, and

Fig. 5 an end view of the hold fast and tripping device; Fig. 6 is a side view, and Fig. 7 an end view of the valve or closing device on the tank, 1. Fig. 8 shows details of one of the collars, 40, supporting the pulley, 36, the other collar being of exactly the same form. These collars, 39, 40, are keyed or suitably secured to the journal, 34, to which the gear, 33, is also keyed or secured. The 10 pulleys, 35 and 36, are provided on their lower faces with suitable recesses to take in suitable pawls, 41, and the collars, 39 and 40, are provided in their upper faces with suitably angled notches, 42, 42, into which drop 15 the pawls, 41, 41. The notches, 42, 42, are sloped so as to allow the pawls, 41, 41, to ride over them, and keep the pulleys, 35, 36, free and out of engagement with the collars when the movement on either pulley is in 20 the direction opposite that indicated by the arrow in Fig. 3. That is, when the tank, 1, descends, and the rope, 20, is passing around the pulley, 35, turning the shaft, 34, and with it the gear, 33, and at the same time 25 taking up the slack of the rope, 16, which passes around the pulley, 36, that pulley, 36, is out of engagement with the collar, 40; but as soon as the tank commences to rise and the rope, 16, commences to do its work and 30 take up the slack of the rope, 20, the pulley, 35, is out of engagement with the collar, 39.

While I have shown one method of utilizing the power developed by means of the device of empty and loaded tanks, I do not 25 limit myself to the same; nor do I limit myself to tanks of any particular size, shape or material, or to any particular number of the same; nor to any number or form of valves for emptying the same or retaining 40 the same empty or loaded, nor to the employment of a rope or chain, or pulleys, for utilizing the power developed, but

Having thus described my invention, what I claim as new and desire to secure by Letters Patent, is—

1. A water or tide motor, including a movable tank provided with an orifice and a suitable valve adapted to open and also to close the same automatically at different 50 points of its movements, substantially as described and shown.
2. In a water or tide motor connected with a suitable operating device, a tank provided with an opening adapted to permit 55 the inflow and outflow of water, in combination with a suitable valve and tripping device for the same, adjusted to permit the outflow of water and then close the opening when the tank is near the low water level, 60 and to open such opening and permit the inflow of water when the tank is near the high water level, substantially as described and shown.
3. A water or tide motor consisting of a 65 suitable frame with guideways therein and

suitable pulleys disposed at the top and at the bottom of such frame, suitable connections disposed around such pulleys, and running toward each other, in combination with a tank provided with opening and 70 closing devices adapted to keep water out of the same when in its lower position and to take in and retain water within the same when in its higher position and attached at its top and at its bottom to such connections, 75 substantially as described and shown.

4. A water or tide motor comprising a tank arranged to float upon the water and having an orifice provided with a suitable valve adapted to be automatically closed to 80 exclude water from the tank when it is at one level, and to be automatically opened to admit and include water therein, when the tank is at another level, substantially as described and shown.

5. In a water or tide motor, a tank provided with one or more openings, each of such openings having a valve adapted to be operated automatically to retain water in said tank at one point of its movements, and 90 to exclude water therefrom at another point of its movements, in combination with suitable attachments to operate a gear wheel disposed upon a suitable journal, such attachments adapted to turn such journal in 95 the same direction at all points of the movement of the tank, substantially as described and shown.

6. A water or tide motor, including a tank adapted to rise empty and light with 100 the rise of the water, and to descend loaded and heavy with the ebb of the water, in combination with an operating device consisting of a journal and gear wheels suitably disposed, such journal having rigidly attached 105 collars, and provided with pulleys free to turn around the journal upon such collars, such collars and pulleys being provided with gravitating pawls and corresponding notches adapted to engage with each other and turn 110 such journal in one direction when the empty tank rises, and in the same direction when the loaded tank descends, substantially as described and shown.

7. A water or tide motor, consisting of a 115 tank adapted to rise light and descend heavy with the ebb and flow of the tide, in combination with flexible connections adapted to operate upon a journal or similar device, and turn such journal in the same direction 120 when the tank rises and when it descends, substantially as described and shown.

8. A water or tide motor, consisting of a tank arranged to rise light and descend heavy with the flow and ebb of the tide, in 125 combination with one flexible connection adapted to operate a mechanical device in one direction when the tank rises, and a flexible connection adapted to operate the mechanical device in the same direction 130

when the tank descends, substantially as described and shown.

9. In a water or tide motor, comprising suitable guideways, a quadrangular tank movable therein and having a bottom substantially flat, one or more openings above such bottom, each of said openings provided with a valve and suitable devices to open and also to close such valve automatically 10 when the tank is at different points of its

movements, in combination with a flexible connection at the upper part and another flexible connection at the lower part of such tank, such flexible connections adapted conjointly to operate a journal or similar device, 15 substantially as described and shown.
